Attorney.

UNITED STATES PATENT OFFICE.

CHARLES J. MUEND, OF PHILADELPHIA, PENNSYLVANIA, ASSIGNOR TO HAINES, JONES & CADBURY INCORPORATED, A CORPORATION OF PENNSYLVANIA.

WASTE MECHANISM AND CONTROL.

Application filed July 16, 1923. Serial No. 651,707.

To all whom it may concern:

Be it known that I, CHARLES J. MUEND, a citizen of the United States, residing at Philadelphia, in the county of Philadelphia, 5 State of Pennsylvania, have invented a new and useful Waste Mechanism and Control, of which the following is a specification.

My invention relates to improvements in a combination supply and waste control. The 10 object is to provide improved arrangement of the waste, and improved controlling means therefor. The invention is especially applicable for bath tubs of the "built-in" type.

15 The invention comprises improved means for controlling the waste valve by operating mechanism located outside the waste pipe, so that said operating parts will not clog the waste passage, and will not be rendered 20 ineffective by accumulations of foreign matter.

25 The invention comprises means adaptable to tubs of varying sizes and having walls of varying inclinations so that a single standard fixture may be fitted to tubs of 30 different designs. This is especially desirable in order to obviate the necessity of carrying in stock a number of different sizes or types of fixtures to assemble with different sizes and designs of tub.

35 The invention also includes an arrangement of parts that will secure symmetrical positioning of the operating handles and, at the same time, a direct alinement of co-acting elements.

40 To this end the invention comprises improvements in details of construction, including means of adjustment and the proper co-ordination of the several co-operating parts.

45 Referring to the drawings, which illustrate, merely by way of example, a suitable embodiment of my invention.

Fig. 1 is a side elevation partly in section of the complete fixture showing its relation to the tub.

Fig. 2 is a rear elevation of same.

Fig. 2^a is a front elevation on a reduced scale, showing the relative positions of the 50 valve handles.

Fig. 3 is an approximately horizontal section on the line 3, 3 of Fig. 1, on an enlarged scale.

Fig. 4 is a horizontal section on line 4, 4 of Fig. 1 on an enlarged scale. 55

Fig. 5 is a vertical cross-section on the line 5, 5, of Fig. 1, on an enlarged scale.

Similar numerals refer to similar parts throughout the several views.

In the construction shown in Figs. 1 and 60 2, the common supply pipe 7 is connected to the hot and cold service, controlled in the usual way by valves, one valve handle being indicated as at 8, in Fig. 2, the other on the left hand end of pipe 7 not being shown. All three valve handles are shown in their relative positions in Fig. 2^a. This common pipe 7 is connected to the pipe 9, 65 which in turn is connected by the elbows 10 and 11 to the pipe 12, threaded throughout its extension as shown. Pipe 12 passes through the opening 13 in the tub 14. To the outer end of pipe 12 is connected the nozzle member 15. The pipe 12 also projects through and is threaded into the rear side 70 of elbow element 16 of the waste overflow. The elbow element 16 is provided with a flange 17 for clamping the washer 18 against the rear side of the tub 14. An escutcheon or shield 19 is interposed between the nozzle 15 and the front face of the tub. This escutcheon is provided with overflow ports, as at 20, in the lower half thereof. It will be obvious that by the proper threaded 75 adjustment between the pipe 12 and the elements 15 and 16, the washer 18 may be put under sufficient pressure, between flange 17 and the wall of the tub surrounding the opening 13, to secure a watertight joint between the tub and the waste element 16. A 80 suitable nut 21 and packing 22 secure a watertight joint between waste element 16 and threaded pipe 12. 85

The overflow waste elbow element 16 is connected, in the usual way to the pipe 23, 90 which in turn joins at the T 24, the waste pipe 25 from the elbow element 26 connected with the waste outlet 27 at the bottom of the tub. The connection between 95 24 and 25 is an adjustable slip joint, as 100 shown in Fig. 4.

It is to be noted that pipe 12, which is threaded throughout its extension, is made of maximum length, that is to permit a maximum distance between the vertical 105 plane of pipe 9 and the inner face of tub

14; this distance being dependent upon the design and size of tub used, and the thickness of wall 28. Where this distance is considerably less than the maximum, it is merely necessary to cut a section from the end of pipe 12. A certain amount of adjustment is also available by the range of threaded extension, as at 29, in the neck or body of nozzle member 15, and also by the space within the nozzle, into which the end of pipe 12 may project.

The washer 18 which is shown tapered from one side to the opposite side may be shifted to compensate for varying inclinations of the wall of tub 14.

It will also be noted that the opening 13 in the wall of tub 14 is larger than the end 30 of elbow element 16, and that the flange 17 is of sufficient extension to permit a considerable variation in the relative position of member 16 with respect to opening 13, and consequently a variation in the inclination of pipe 12. The elbows 10 and 11 are not both right angle elbows, one being approximately of forty-five degrees. Elbow 10 has preferably a slip joint connection with pipe 9, similar to the adjustable slip joint shown between 24 and 25, in Fig. 4. These several factors facilitate in a proper relative adjustment between pipe 9, elbow 16, pipe 12 and nozzle 15, and greatly facilitate their assembly with tubs of varying designs and sizes.

The main waste outlet 27 in the bottom of the tub is provided with the valve member 31. This valve member 31 comprises the winged formation 32, having the central opening or channel 33, into which the stem of pin 34 projects upwardly. This stem is engaged at its upper end with the screw 35 which passes through the top of plate 36. The threaded opening 37 is of sufficient depth to allow adjustment of the screw 35, to bring the plate 36 into tight engagement with the washer 38, which lies between the plate 36 and the top of formation 32, and forms the valve proper which cooperates with the seat 39 fitted into the opening 27, by threaded engagement with elbow element 26. The lower end of pin 34 is provided with the head 40 which engages with the actuating lever 41, secured, in any suitable way, to the rock-shaft 42, which extends into the housing 43, formed integral with the elbow element 26. An opening 44 communicates with housing 43 and the interior of 26. The shaft 42 is further housed in the tubular housing 45 which is threaded into the housing 43 as shown in Fig. 4. This tube 45 is supported near its outer end in the bracket 46 connected to the T 24. The outer extreme end of tube 45 is provided with the nut or cap 47, threaded on to said end, having a

central opening forming a bearing for the rock-shaft 42, and provided with packing as at 48, to form a watertight joint. Near the outer end of rock-shaft 42 is secured the arm or lever 49 by means of the set-screw 50 in any desired position of horizontal adjustment. This lever 49 is pivotally connected, as at 51, to the connecting rod 52. To the upper end of rod 52 is secured the member or yoke 53, by a threaded adjustable engagement; there being a long threaded extension on the rod, as at 54, to provide ample means for said adjustment. The lock nut 55 provides means for maintaining the adjustment desired. The upper end of member 53 is provided with the slot 56 and the finger or projection 57.

A shaft 58, connected with the waste valve handle 59, is suitably journaled through the wall 28, as indicated in Fig. 1, and is provided at its inner end, with the eccentric member 60 keyed thereto by set-screw 61. This member 60 is provided with the eccentric pin 62 projecting into slot 56, and with the stop pin 63. A screw 64 and washer 65 serve to secure member 53 upon eccentric pin 62. In Fig. 2 the eccentric member is shown in the position holding the valve member 31 in the elevated or open position, the stop pin 63 engaging the side of the yoke, to limit the eccentric member 60 in its lifting valve opening movement. The stop 63 will engage the projection 57 to limit the rotative movement of the eccentric member 60, in the opposite direction.

As already pointed out, tubs of the class referred to, vary considerably in design and size; for example, where the inclination of the end wall is greater, the waste opening in the bottom is further removed from the vertical back wall, and the thickness of this wall may also vary. It follows that the connecting elements between the waste-valve handle 59 and the valve member 31, must be adjusted accordingly. For this purpose the shaft 42 is made of sufficient length to accommodate the maximum distance required, and where the distance is considerably less than the maximum, the lever 49 is properly located and secured to shaft 42 and the end of the shaft 42, projecting beyond said lever 49, is cut off.

Since it is desirable, as a preferred construction, to position the valve handles 8, 59 and 8, symmetrically, with respect to the nozzle 15, it follows, that handle 59 should be in the same middle plane of the tub, with nozzle 15, and that the connecting rod 52 should also operate in substantially the same plane. To secure this arrangement it will be noted that the supply pipe 9 is connected to the common hot and cold water pipe 7, at one side of said middle plane, and the double-elbow formation 10,

11, permits the connection to pipe 12 and nozzle 15, without interfering with the connecting rod 52.

I do not wish to limit my invention to the specific arrangement shown in the drawings, except as to the claims defining such arrangement.

What I claim is:—

1. In combination with a bath tub, having a waste outlet, a valve for controlling said outlet, a horizontal waste pipe connected with the outlet, a valve actuating arm, a rock-shaft for actuating said arm, extending outside of and parallel with the horizontal waste pipe, and means for arbitrarily operating said shaft.
2. In combination with a bath tub, having a waste outlet, a valve for controlling said outlet, a horizontal waste pipe connected with the outlet, a valve actuating arm, a rock-shaft for actuating said arm, extending outside of and parallel with the horizontal waste pipe, and a housing for said shaft, associated with the waste pipe.
3. In combination with a bath tub, having a waste outlet, a valve for controlling said outlet, a horizontal waste pipe connected with the outlet, a valve actuating arm, a rock-shaft for actuating said arm, extending outside of and parallel with the horizontal waste pipe, and a housing for said shaft, associated with the waste piping, and a bearing for said shaft associated with the housing.
4. In combination with a bath tub, having a waste outlet, a valve for controlling said outlet, a horizontal waste pipe connected with the outlet, a valve actuating arm, a rock-shaft for actuating said arm, extending outside of and parallel with the horizontal waste pipe, and a housing for said shaft, associated with the waste piping, enclosing the greater part of the shaft extension.
5. In combination with a bath tub, having a waste outlet, a valve for controlling said outlet, a horizontal waste pipe connected with the outlet, a valve actuating arm, a rock-shaft for actuating said arm, extending outside of and parallel with the horizontal waste pipe, and a housing for said shaft, connected to and supported by the waste piping.
6. In combination with a bath tub, having a waste outlet, a valve for controlling said outlet, an elbow connected with the outlet and providing a housing at one side thereof, a horizontal waste pipe connected with the elbow, a valve actuating arm, a rock-shaft for actuating said arm, extending from said housing outside of and parallel with the horizontal waste pipe, and a tubular water-tight housing for said shaft, extending from

said elbow housing to near the outer end of said shaft.

7. In combination with a bath tub, vertical and horizontal waste pipes connected thereto, a waste outlet, a waste valve therefor, a valve actuating member, an actuating rock-shaft therefor extending outside and parallel with the horizontal waste pipe and means for arbitrarily operating said actuating shaft.

8. In combination with a bath tub, vertical and horizontal waste pipes connected thereto and having adjustable connection with each other, a waste outlet, a waste valve therefor, a valve actuating member, an actuating rock-shaft therefor extending outside and parallel with the horizontal waste pipe and means for arbitrarily operating said actuating shaft.

9. In combination with a bath tub, vertical and horizontal waste pipes connected thereto and having adjustable slip joint connection with each other, a waste outlet, a waste valve therefor, a valve actuating member, an actuating rock-shaft therefor extending outside and parallel with the horizontal waste pipe and means for arbitrarily operating said actuating shaft.

10. In combination with a bath tub, vertical and horizontal waste pipes connected thereto and having their axes in the middle plane of the tub, a waste outlet, a waste valve therefor, a valve actuating member, an actuating rock-shaft therefor extending outside and parallel with the horizontal waste pipe and means having adjustable connection with the actuating shaft for arbitrarily operating the same.

11. In combination with a bath tub, vertical and horizontal waste pipes connected thereto, a waste outlet, a waste valve therefor, a valve actuating member, an actuating rock-shaft therefor extending outside and parallel with the horizontal waste pipe, means connected to the waste piping forming a bearing for said actuating shaft and means for arbitrarily operating said actuating shaft.

12. In combination with a bath tub, having vertical and horizontal waste pipes connected thereto, and adjustably connected to each other, a waste outlet, a waste valve, a valve actuating member, an actuating rock-shaft therefor extending outside and parallel with the horizontal waste pipe, operating means for said shaft, including a vertical rod supported in the middle plane of the tub and means for establishing horizontally adjustable operative relationship between the said vertical rod and the said actuating shaft.

CHARLES J. MUEND.
